M. P. & L. E. LITTLE.
BURIAL CASKET.
APPLICATION FILED JULY 20, 1911

1,026,044.

Patented May 14, 1912.

UNITED STATES PATENT OFFICE.

MINNIE PEARL LITTLE AND LUAR EDNA LITTLE, OF COLUMBIA, MISSOURI.

BURIAL-CASKET.

1,026,044.

Specification of Letters Patent.

Patented May 14, 1912.

Application filed July 20, 1911. Serial No. 639,618.

To all whom it may concern:

Be it known that we, MINNIE PEARL LITTLE and LUAR EDNA LITTLE, citizens of the United States, residing at Columbia, in the county of Boone and State of Missouri, have invented certain new and useful Improvements in Burial-Caskets, of which the following is a specification.

This invention relates to improvements in burial caskets, an object of which is to provide a casket which will resist the action of time and erosion, and which is adapted to be hermetically sealed.

Another object is to provide a burial casket made out of cement or other plastic composition, the walls of which are peculiarly reinforced, thereby insuring strength to the casket and economy in manufacture.

The casket includes, as usual, a cover adapted to be hermetically sealed which is firmly held in place by an adjustable surrounding band peculiarly adapted for the purpose; said band being carried by the casket in coöperation with a hinged portion 25 into which the reinforcing strap is formed.

With these and other objects in view, this invention consists in the combination, construction, and arrangement of parts, all as hereinafter more fully described, claimed 30 and illustrated in the accompanying drawings, wherein—

Figure 1 is a perspective view of a coffin embodying the present invention; Fig. 2 is a transverse section; Fig. 3 is a longitudinal section; Fig. 4 is a top plan view of the reinforcing member; and Fig. 5 is a fragmentary perspective of the band.

Throughout the following detail description and on the several figures of the drawings, similar parts are referred to by like reference characters.

As stated above, an important object of this invention is to make a coffin which will practically withstand the action of time and destructive elements, and in order to obtain this result combined with minimum expense, concrete or other suitable plastic composition is used. However, in order that the above results shall be fully acquired, certain reinforcing elements are employed, the peculiarly advantageous construction of which will hereinafter appear.

Referring to the drawings, at 1 is indicated the burial casket and at 2 the cover therefor, the latter adapted to be placed on

top of the casket and the rounded tongue and groove joint 3 hermetically sealed.

A plurality of U-shaped reinforcing members 4 are embedded in the bottom and extend upwardly in the sides of the coffin to a point slightly below the top edge of said coffin where the ends 5 are bent outwardly and extend beyond the surface of the walls. The bent portions 5 are slotted, as at 6, to form spaced extensions 7. To give additional strength to the coffin, straps 8 are provided, each having a bottom part 9 and a top part 10. The part 9 is formed with a threaded extension 11 at one end thereof, and with a flange 12 at the opposite end, said flange having an opening therethrough. At a point coinciding with the extensions 7 of the reinforcing straps 4, the band member 9, which is in the form of a metallic plate, has cut in opposite edges thereof notches 13 adapted to receive said extensions 7, the latter being rolled to form ears 14. The ears 14 serve the double purpose of holding the band member 9 in place and having hinged thereto the handles 15.

The band member 10 has a flange 16 formed with an opening to register with the opening in the flange 12, said openings being adapted to receive a clamping bolt 17. Opposite to the flange 16 the member 10 has hinged thereto an elongated nut 18 which is slightly curved to conform to the curvature of the rounded corner of the coffin cover and adapted to receive the threaded extension 11 of the band member 9. The cover is reinforced by bars 19.

It will be seen that the ears 14, which may be sufficiently spread apart to admit of assembling the parts 4 and 9, or which ears may be formed after assembling of said parts, will afford a most substantial fastening means for the band, and by engagement with the latter, the ears are substantially braced thereby affording a rigid hinge for the coffin handles. The adjustable feature of the band 8 is of advantage when sealing the joint between the cover and casket, inasmuch as it will allow for variation in size of the cover.

Having thus fully described our invention, what is claimed as new is—

1. A coffin formed of plastic material and having a reinforcing member in the walls thereof, a bent portion of said reinforcing member extending beyond the surface of the

wall and formed with ears, a handle carried by said ears, and metallic bands having oppositely disposed notches, said notches adapted to engage the bent portions of the 5 reinforcing members and said ears adapted to keep the band in place.

2. A coffin formed of plastic material having a metallic band, said band including a cover retaining part and a bottom part adjustably connected, the bottom part having notches cut therein, a reinforcing member co-operating with said notches for keeping the band in place.

3. A coffin formed of plastic material 15 having a metallic surrounding band comprising a cover retaining part, a bottom part adjustably connected thereto, a reinforcing member embedded in the plastic material of the coffin having its opposite ends protrud-

ing from the body of said coffin and coöperating with the bottom part aforesaid to prevent displacement of the said surrounding band.

4. A coffin formed of plastic composition including a metallic band formed of a bottom and a top part which parts have adjustable connecting means, said means consisting of an elongated nut curved and hinged to the aforesaid top part, the said bottom part having a threaded extension to 25 engage the said nut.

In testimony whereof we affix our signatures in presence of two witnesses.

MINNIE PEARL LITTLE.
LUAR EDNA LITTLE.
